UNITED STATES PATENT OFFICE.

JOHN AULD, OF CHICAGO, ILLINOIS.

ERASER STRUCTURE.

1,298,639.

Specification of Letters Patent.

Patented Apr. 1, 1919.

Application filed February 6, 1919. Serial No. 275,478.

To all whom it may concern:

Be it known that I, JOHN AULD, a citizen of the United States, and a resident of Chicago, in the county of Cook and State of Illinois, have invented certain new and useful Improvements in Eraser Structures, of which the following is a specification.

My invention relates to eraser structures, and particularly to improved holders and brush attachments therefor.

Although my invention may be employed in connection with different types of erasers, it is particularly desirable in connection with the circular disk type of eraser.

15 The object of the invention is to provide a sheet metal supporting frame for the eraser, together with a handle or holder hinged to the frame, for affording better hold for guiding and steadyng the eraser and for permitting more accurate use thereof. The handle or holder structure may have a brush secured thereto, and another feature of the invention involves the improvement of forming the brush.

20 The various features of the invention are shown in the accompanying drawings, in which—

Figure 1 is a side elevational view of the eraser structure, involving an eraser disk, supporting frame and handle.

Fig. 2 is an edge view of the structure of Fig. 1.

Fig. 3 is a side elevational view showing a brush secured to the holder.

35 Fig. 4 shows a modified form of supporting frame.

Fig. 5 is a sectional view on line 5—5 of Fig. 4.

Figs. 6, 7 and 8 show various steps in the 40 formation of the brush and holder, and

Fig. 9 is a plan view of another form of the eraser structure to which my invention is applied.

Referring to Figs. 1 and 2, the eraser structure comprises the circular rubber disk 10, the supporting frame 11 and the wire holder 12. The supporting frame is of sheet metal and is of U-shape. The limbs of the frame have at their ends openings for registering with the center opening usually found in circular eraser disks, a tubular rivet 13 extending through the openings to secure the eraser disk to the frame for rotation therein so that different surfaces of the

eraser may be presented for use. The holder 12 is of U-shape and is bent from a piece of wire, its ends 14 and 15 being deflected inwardly into coincident lines to form pivot trunnions. The frame 11 at its bend is formed to provide the opposite pivot openings 16 and 17 for the trunnion ends 14 and 15. The wire holder is normally sprung so that when it is applied to the supporting frame its sides will be spread apart to afford spring pressure against the supporting frame. It is very desirable that when the eraser is not in use the holder should assume a neutral position to lie in the plane of the eraser disk, but to yield to swinging movement so that the structure can be readily grasped and its parts swung relatively during use.

In Figs. 1 and 2 this is accomplished by diagonal cutting away of the corners at the bend of the supporting frame 11, thus leaving diagonal cam surfaces which cause spreading apart of the holder sides when it is swung, the tendency being then to keep the holder extending away from the frame and in the plane thereof.

In Fig. 3 the holder 12 is shown supporting the brush cup 18 from which the bristles 19 extend and additional means in the form of a thin flat spring 20 is provided for keeping the holder yieldingly in neutral position. This spring is shown secured to the cup 18 at its upper end, extends at its lower end between the sides of the frame 11 through the notch 21 formed in the bend of the frame. When the brush is to be used for cleaning purposes the eraser structure may be held by the frame 11. The flexible yielding or spring hinge connection of the brush holder and the frame permits a more yielding and softer application of the brush to typewritten documents.

In the arrangement of Figs. 4 and 5 the eraser disk 10 is reinforced by the side plates 22 and 23, secured together by the tubular rivet 24 and the frame 11 has detachable connection with the eraser, and at the ends of its limbs has the beads or projections 25 and 26 pressed therefrom which forms trunnions for engaging in the ends of the rivet 24 where the frame is applied. With this arrangement the cam corners on the frame 11 are preferably omitted in order to prevent spreading apart of the frame when the

holder 12 is swung, and only the spring 20 is relied upon for keeping the holder normally in its neutral position.

In Figs. 6, 7 and 8 the manner of forming the holder and forming and securing the brush thereto is shown. A length of wire is first bent into the form of a hairpin, and its bent end is slipped through the opening 27 in the base of the cup 18. A bundle of bristles 29 is then inserted through the bend of the wire and the wire then pulled downwardly into the cup; thus bending the bundle of bristles at the middle and bringing the two ends thereof together to form the brush. The cup is then flattened to secure the bristles therein and the ends of the wire are then bent to form shoulders 30 and 31 for engaging with the cup to prevent displacement thereof. The wire is then further bent to form its parallel sides and the trunnion ends 14 and 15.

Fig. 5 shows more clearly the manner of securing the spring 20, the upper end of the spring being inserted through the opening 27 to be clamped and secured when the cup is flattened. When the holder is applied to the supporting frame 11 the lower end of the spring is slipped through the slot 21 into position between the frame sides.

In Fig. 9 my improved brush holder is shown applied to an eraser of the flat oblong type, in which a strip 32 of erasing rubber is adjustable within the rectangular frame 33. The frame is provided with opposite openings 34 and 35 at one end for receiving the turned in ends 14 and 15 of the holder 12, which may or may not have a brush secured thereto.

The frame 11 is preferably made of sufficient length, that is it extends a sufficient distance beyond the eraser disk periphery to afford ample grasping surface without touching the eraser disk, and the holder 12 is also of sufficient length to be readily grasped between the fingers so that the frame may be swung to the desired angle and erasing accomplished with accuracy and precision. Whenever the eraser is released from the hand the spring hinge connection between the frame and holder will cause the holder to extend outwardly in the plane of

the eraser disk so that the eraser structure is always in proper position to be taken in hand.

I do not desire to be limited to the exact 55 constructions and arrangements herein described and referred to, as changes and modifications can no doubt be made and still come within the scope of the invention.

I claim as follows:

1. The combination with an eraser, of a supporting frame therefor, and a handle spring hinged thereto.

2. A supporting structure for erasers comprising a U-shaped frame for receiving the 65 eraser between its ends, and a holder hinged to said frame at the bend thereof.

3. A supporting structure for erasers comprising a U-shape frame for clamping an eraser between its ends, a holder hinged to 70 said frame to form an extension thereof, and a brush secured to said holder.

4. A supporting structure for erasers comprising a U-shaped frame for clamping an eraser between its ends, a wire holder hinged 75 to the end of said frame to form an extension thereof, and yielding means normally holding said holder extended and in the plane of said frame.

5. A supporting structure for erasers comprising a U-shape clamping frame, a holder hinged to said frame at its bend to form a continuation thereof, and a spring extending between said holder and frame tending to hold said holder extended in the plane of 85 said frame.

6. A supporting structure for erasers comprising a U-shape frame for clamping an eraser between its ends, a U-shape holder having its ends inserted into the opposite 90 ends of the bend of said U-frame, whereby said holder is hinged to said frame to form a continuation thereof, the corners at the bend of said frame being cut away diagonally to present cam surfaces to the end of 95 said holder whereby said holder will normally be held extended from and in the plane of said frame.

In witness whereof, I hereunto subscribe my name this 3rd day of February, A. D., 100 1919.

JOHN AULD.
